MULTIPLE POWER TOOL FOR FABRICATING METAL TUBING OR THE LIKE

John Calvin Gallop, Jr., Norfolk, Va.

Application January 20, 1954, Serial No. 28,612

Term of patent 14 years

(Cl. D54—14)

FIG. 1.

FIG. 2.

To all whom it may concern:

Be it known that I, John Calvin Gallop, Jr., a citizen of the United States and a resident of Norfolk, Virginia, have invented a new, original, and ornamental Design for a Multiple Power Tool for Fabricating Metal Tubing or the like, of which the following is a specification, reference being had to the accompanying drawings, forming a part hereof.

Figure 1 is a front perspective view, and

Figure 2 is a rear perspective view of a multiple power tool for fabricating metal tubing or the like embodying my new design.

I claim:

The ornamental design for a multiple power tool for fabricating metal tubing or the like, as shown.

No references cited.
